(57) **CLAIM**

The ornamental design for a color display system, as shown and described.

DESCRIPTION

FIG. 1 is a front perspective view of a color display system;
FIG. 2 is a front view thereof;
FIG. 3 is a back view thereof;
FIG. 4 is a right side view thereof;
FIG. 5 is a left side view thereof; and,
FIG. 6 is a top plan view thereof.

The broken lines showing in FIGS. 1 through 6 are for illustrative purposes only and form no part of the claimed design.
